Primary Examiner — Eric L Goodman*Assistant Examiner* — Sanjeev Paul(74) *Attorney, Agent, or Firm* — Thomas B. Ryan; Harter Secrest & Emery LLP**CLAIM**

The ornamental design for a smart glasses, as shown and described.

DESCRIPTION

FIG. 1 is a top, front, and left side perspective view a smart glasses showing our new design.

FIG. 2 is a top, back, and right side perspective view thereof.

FIG. 3 is a top plan view thereof.

FIG. 4 is a bottom plan view thereof.

FIG. 5 is a front elevational view thereof.

FIG. 6 is a back elevational view thereof.

FIG. 7 is a left side elevational view thereof; and,

FIG. 8 is a right side elevational view thereof.

The broken lines showing features on the inside of the nose bridge and temple arms are for the purpose of illustrating unclaimed portions of the smart glasses and form no part of the claimed design.
